BATHTUB HANGER

William B. Lucke, Wilmette, Ill.

Application February 10, 1932, Serial No. 592,056

8 Claims. (Cl. 4—173)

This invention relates to improvements in hangers for holding and securing a bathtub in position, and one of the objects of the same is to provide an improved hanger of this character by means of the use of which the weight of the bathtub will be borne directly by the studding and not by the floor, and which studding also supports the plastering or tiling, thereby obviating the danger of relative displacement of one with respect to the other, caused usually by the settling of the floor with the shrinking of the floor joists and which settling results in the formation of crevices or cracks between the edge of the bathtub and the wall of the room.

15 A further object of the invention is to provide an improved hanger of this character which will maintain a tight sealing joint, thereby preventing water seepage around the edge of the tub.

20 A further object of the invention is to provide an improved hanger of this character which will maintain the tub in its originally set position, regardless of the amount of settling of the building.

25 A further object is to provide improved means for maintaining the tub from tilting under the stress of excessive weight applied to any portion thereof.

30 A still further object is to provide an improved supporting hanger of this character having adjustably connected parts which will not only compensate for tubs having different sized rims, but will facilitate in the application and adjustment of the device.

35 To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

40 Figure 1 is a vertical, transverse sectional view of a bathtub showing the same secured and held in position by means of hangers constructed in accordance with the principles of this invention.

45 Figure 2 is a detail perspective view, on an enlarged scale, of a portion of the tub and one form of hanger for securing the tub in position.

50 Figure 3 is a perspective view of a supporting hanger member.

55 Figure 4 is a detail perspective view of a clamping member which co-operates with the hanger.

Figure 5 is a perspective view of the fastening bolt for securing the parts of the hanger together in clamping relation.

Figure 6 is a vertical sectional view of a portion of a bathtub showing another form of the invention.

Figure 7 is a view similar to Figure 6, showing another form of the invention.

Figure 8 is a sectional view similar to Figure 6, showing another form of the invention.

Figure 9 is a view similar to Figure 6, showing still another form of the invention.

Figure 10 is a detail perspective view of another form of hanger showing the parts assembled.

Figure 11 is a view similar to Figure 6, of still another form of hanger.

Referring more particularly to the drawings and in the forms of the invention shown in Figures 15 3 to 5, the hanger consists essentially of a body portion 15 formed of any suitable material and is of any desired length and width, the lower extremity thereof being deflected laterally as at 16 to form a supporting portion and through which 20 portion 16 is provided an opening 17. In the body portion of the hanger openings 18 are provided and by means of which openings 18 the hanger may be secured to a studding or support 19 by means of suitable fastening bolts or screws 20. 25

The projecting portion 16, when the hanger is secured in position extends under the rim 21 of the bathtub 22 and any number of these hangers 15 may be employed and spaced for any desired distance from each other so as to be engaged by 30 the tub on one or more sides and by means of which hangers the tub will be suspended by the uprights or joists 19 and spaced above the floor 22 of the room.

If desired a plate 23 may be secured to the 35 joists or uprights 19 over the hangers 15 and which plate is provided with suitable apertures 24 providing a means for the formation of keys on the plaster or wall covering, or as a means for locking tiling in position. This plate 23 is of 40 any suitable width and may be formed with an upwardly opening hook shaped portion 25 along the lower edge thereof so as to rest upon the laterally deflected portion 16 of the hanger 15 and to engage with the lower end of the hanger 45 under the rim 21 of the tub.

Co-operating with the hanger 15 is a clamp member 26 provided with slots or elongated openings 27 in the body portion thereof and a laterally deflected lower extremity 28 having an 50 opening 29 therethrough.

When the tub is in position the rim 21 will engage and rest upon the hook shaped portion 25 of the plate 23 if the latter is used, and if not then upon the laterally deflected portion 16 of 55

the hanger 15, and any suitable sealing material 30 may be provided for forming a fluid tight joint between the rim or edge of the tub and the wall of the room so as to prevent water seepage. After the sealing material 30 has been placed in position, the clamp member 26 is applied and secured in position by means of fastening bolts or screws 31 passing through the slots 27 and also through certain of the openings 18 in the body of the hanger 15 and into the joists or uprights 19, and when the clamp member 26 is in position the laterally deflected portion 28 will project over the top edge of the rim of the tub. If desired, suitable packing 32 may be employed and arranged between the surface of the tub and the lower face of the deflected portion 28 of the clamp member 26, thereby not only serving as a means to form a liquid tight joint but also as a cushioning means to prevent injury to the tub by the clamp member.

A fastening bolt 33 provided with a head 34, is inserted through the registering openings 29-17 of the portion 28 of the clamp member 26 and of the portion 16 of the hanger 15, so that the head will engage the upper surface of the portion 28 of the clamp member and the bolt is of a sufficient length to project below the portion 16 of the hanger. A thumb or wing nut 35 is threaded upon the bolt 33 and by the adjustment of the nut 35, it will be manifest that the clamp member 26 will be drawn toward the portion 16 of the hanger and thereby effect a clamping of the rim of the bathtub to the hanger. The bolt 33 is preferably applied before the sealing material 30 is placed in position. In applying the clamp member the screws or bolts 31 are adjusted so as to permit the clamp member to slide freely into clamping position under the influence of the action of the nut 35, after which the screws or bolts 31 are tightened so as to hold the parts firmly in position.

In the form of the invention shown in Figures 2 and 6, the laterally deflected portion 36 of the hanger is provided with an upwardly curved forward edge 37 which engages well under the rim of the tub and the sealing material 30 may be placed between the edge 37 of the hanger and the rim 21 of the tub.

With this form of the invention it will be manifest that the clamping member 26 will force the rim of the tub against the laterally deflected portion 36 of the hanger and the fastening bolt 33 will be disposed in close proximity to the peripheral edge of the rim, with the result that the bolts 33 also serve as a means for assisting in preventing the tub from tilting with respect to the hangers.

In the form of the invention shown in Figure 7, the plate 23 is provided with a laterally deflected portion 39 adjacent the bottom thereof, and a downwardly projecting portion 40 terminating in an upwardly opening hook shaped portion 41, the portion 41 engaging and resting upon the laterally deflected portion 36 of the hanger while the deflected portion 39 will be spaced above the portion 36 of the hanger and is provided with an opening 42 through which the fastening bolt 33 passes.

In this form of the invention the clamping member 43 is provided with a laterally deflected portion 44 and a downwardly extending edge 45 so as to engage over the rim 46 of the tub, in a manner to force the lateral edge of the tub rim against the downwardly projecting or upright portion 40 of the plate 23 so that any strain

caused by the tendency of the tub to tilt with respect to the hanger would be resisted by the upright portion 40 of the plate 23, and the fastening bolts 33 would be relieved of all strain caused by such tendency to tilt.

Filling material 30 may be employed between the parts to form liquid tight joints.

In the form of the invention shown in Figure 8, the plate member 23 is provided with a cut out portion deflected laterally as at 48, shaped to co-operate with a laterally deflected portion 49 at the lower end of the plate. These deflected portions 48-49 engage over the rim of the tub 22 to form a clamp and a fastening bolt 50 having a head 51 passes through registering apertures in the portions 48-49 and is provided with a nut 52 on the end thereof by means of which the portions 48-49 may be drawn towards each other, suitable packing 53 being employed if desired, and filling material 30 may also be used.

In this form of the invention an adjusting screw 55 is threaded through the laterally deflected portion 56 of the hanger member 57 and engages under the rim of the tub, serving as a means for forcing the rim of the tub between the portions 48-49 of the hanger. A lock nut 58 may be provided for holding the screw 55 in its adjusted position.

In Figure 9 there is shown another form of hanger 59 having a hook shaped portion 60 at the lower end thereof and the plate 23 is provided with an upwardly opening hook shaped extremity 61 seated within the hook shaped portion 60 of the hanger, a clamp member 62 co-operating with the hook shaped portion of the hanger for clamping the rim 63 of the tub. A fastening bolt 64 tends to draw the clamping member toward the hook shaped portion of the hanger and suitable sealing material 30 is employed to form a liquid tight joint.

In this form of the invention a screw 66 is threaded through a portion of the hook shaped extremity of the hanger and engages the lower face of the flange 63 of the tub and tends to force the rim or flange of the tub between the clamp 45 and the hook shaped portion 60 of the hanger, a lock nut 67 being employed to hold the screw 66 in its adjusted position.

In Figure 11 there is shown a modified form of the invention somewhat similar to the construction shown in Figure 8, in which the plate 23 is provided with a cut out portion 68 deflected downwardly so as to co-operate with an upwardly opening hook shaped portion 69 at the lower edge of the plate. The rim 70 of the tub passes between the portions 68 and 69, and packing or sealing material 30 may be arranged between the portions 68 and the upper surface of the tub, and sealing material 72 being employed to form a liquid tight joint. In this form of the invention a screw 73 is threaded through the upwardly opening hook shaped portion 74 of the hanger 75 to engage under the lower edge of the rim of the tub, and a lock nut 76 may be employed for holding the screw 73 in its adjusted position.

Any number of these hangers may be employed and may be suitably arranged, and when in position it will be manifest that the tub will be supported or suspended from the uprights or joists of the building and in such a manner that all settling of the tub with respect to the wall or plaster or tiling will be prevented, and which settling generally occurs by shrinking of the floor upon which the tubs usually sit and a shrinking of the floor joists.

Furthermore, all seepage of water between the edge of the tub and the wall will be prevented by the sealing material, and by the use of these hangers and the distribution and arrangement of the same at different points around the periphery of the tub, it will be manifest that the tub will be held against any tendency to tilt due to any excessive strain or heavy weight placed upon any one portion of the tub, as the hanger members and the co-operating clamping devices serve as a means for preventing such tilting movement.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. A bathtub hanger comprising a supporting bracket provided with an upwardly opening hook shaped portion for suspending the tub above the floor and into which hook shaped portion the rim of the tub engages, means securing the hanger to an upright, a clamp connected with the hanger and engaging over the bathtub rim and co-operating with said hook shaped portion to clamp the rim therebetween, and a fastening device passing through the said clamp and the body of the hook shaped portion and beyond the edge of the bathtub rim.

2. A bathtub hanger comprising a supporting bracket provided with a laterally projecting portion for engaging under a bathtub rim for suspending the tub above the floor, means securing the hanger to an upright, a clamp element for engagement with the top edge of the tub and co-operating with said laterally projecting portion to clamp the tub rim therebetween, means for adjustably securing the clamp member to said hanger, and a fastening element passing through said clamp member and the body of the hook shaped portion beyond the edge of the tub rim.

3. A device of the character described embodying a hanger member having a laterally projecting supporting portion upon which the rim of a bathtub rests whereby the tub will be suspended thereby independently of the floor, means securing the hanger member to an upright, a clamp member connected with the hanger member and engaging over the top of said rim and co-operating with the laterally projecting portion to hold the rim therebetween, and means engaging said clamp member and said laterally projecting portion of the hanger for drawing them into clamping relation.

4. A device of the character described embodying a hanger member having a laterally projecting supporting portion upon which the rim of a bathtub rests whereby the tub will be suspended thereby independently of the floor, means securing the hanger member to an upright, a clamp member connected with the hanger member and having

a laterally projecting portion engaging over the top of said rim and co-operating with the first said laterally projecting portion to hold the rim therebetween, means engaging said clamp member and said laterally projecting portion of the hanger for drawing them into clamping relation, and sealing material between the outer edge of the tub and the adjacent parts of the clamp and hanger member.

5. A bathtub support embodying a hanger member provided with a laterally projecting portion to engage under the rim of a bathtub to suspend the tub with respect to a floor, means securing the hanger to an upright, a clamp member connected with the hanger and engaging over the edge of the tub and co-operating with said laterally projecting portion to hold the tub rim therebetween, and an adjusting screw threaded through said laterally projecting portion beneath said rim and engaging the lower face of the rim.

6. A bathtub support embodying a hanger member provided with a laterally projecting portion to engage under the rim of a bathtub to suspend the tub with respect to a floor, means securing the hanger to an upright, a clamp member connected with the hanger and engaging over the edge of the tub and co-operating with said laterally projecting portion to hold the tub rim therebetween, means adjustably securing the clamp member with the hanger, a fastening bolt passing through the clamp member and the body of the laterally projecting portion of the hanger, and an element adjustably connected with said laterally projecting portion beneath said rim and engaging the lower face of the rim.

7. A tub holding bracket comprising a wall engaging element having an outwardly projecting flange to engage under the tub rim, a flange clamp slidably mounted adjacent the face of said element and having an outwardly projecting flange to engage over and rest upon the top of the tub rim, and means for securing the clamp in adjusted position, said means embodying a fastening device passing through an elongated opening in the clamp and also through the said wall engaging element and into the supporting wall.

8. A tub holding bracket comprising a wall engaging element having an outwardly projecting flange to engage under the tub rim, a flange clamp slidably mounted adjacent the face of said element and having an outwardly projecting flange to engage over and rest upon the top of the tub rim, means for securing the clamp in adjusted position, said means embodying a fastening device passing through an elongated opening in the said clamp and engaging the said element, and additional means engaging the said element and the clamp beyond the edge of the tub for drawing said element and clamp against the rim of the tub.

WILLIAM B. LUCKE.
